UNITED STATES PATENT OFFICE.

ALLEN W. HELMS, OF AYLESWORTH, INDIANA.

BRIDLE-BIT.

SPECIFICATION forming part of Letters Patent No. 389,809, dated September 18, 1888.

Application filed June 30, 1888. Serial No. 278,615. (No model.)

To all whom it may concern:

Be it known that I, ALLEN W. HELMS, a citizen of the United States, residing at Aylesworth, in the county of Fountain and State of Indiana, have invented certain new and useful Improvements in Bridle-Bits; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

15 This invention relates to bits for horses, and has for its object the provision of a bit which will be capable of inflicting severe punishment on an animal when he becomes unruly, and which will lessen the labor incident to driving 20 a fiery steed having a tough mouth.

The improvement consists in the novel features which hereinafter will be more fully described and claimed, and shown in the drawings, in which—

25 Figure 1 is a perspective view of a horse's head, showing the application of my bit; Fig. 2, a perspective view of the bit, and Fig. 3 a cross section of the side bars on the line X X of Fig. 2.

30 The side bars, A, taper in cross section from their outer to their inner edges, and have openings at each end to receive the rings B and B', respectively, and notches a in their inner edges midway of their ends. The staples or keepers

35 C are secured to the side bars, and have the notches a located between them, as shown. The mouth-bars D are secured at one end to

one of the side bars, and have their free ends passing loosely through the staples C on the other side bar and provided with the links d. 40 The edges of the back or lower half of the side bars are serrated, or provided with the saw-teeth e, which are adapted to be pressed into the jaws of the animal and inflict punishment.

In practice the headstall F is secured to the 45 keepers C, the reins I to the links d, the over-draw or check G to the rings B', and the short check H between the headstall and the bit to the rings B.

Having thus described my invention, what I 50 claim, and desire to secure by Letters Patent, is—

1. The herein-described bit, composed of the side bars having rings at each end and staples between their ends, and the mouth-bar comprising two separate bars, each connected at one end to one of the side bars, and having their other ends free and passed through the staples on the other side bars and provided with rings, substantially as described. 55

2. The combination, with the side bars having their inner edges serrated and provided with staples, of the mouth-bar comprising two separate bars, having one end of each passed through the staples of one bar, and having its 65 other end secured to the other side bar, substantially as shown.

In testimony whereof I affix my signature in presence of two witnesses.

ALLEN W. HELMS.
